EDWARDS CORRUGATING COMPANY, OF COVINGTON, KENTUCKY, A CORPO-
RATION OF KENTUCKY.

METAL WINDOW FRAME AND SASH.

1,199,495.

Specification of Letters Patent. Patented Sept. 26, 1916.

Application filed March 13, 1915. Serial No. 14,261.

To all whom it may concern:

Be it known that I, EDWIN R. PROBERT, a citizen of the United States of America, and a resident of Covington, in the county 5 of Kenton and State of Kentucky, have invented a certain new and useful Improvement in Metal Window Frames and Sashes, of which the following is a specification.

This invention relates to windows and 10 frames made of sheet-metal bent or shaped so as to provide hollow insulator air-chambers wherever possible and of a type whose object is to provide for lateral adjustability of the sash run-ways in the side-jambs 15 of the frame to compensate for the expansion and contraction of the material and for the settling of the building-structure to meet fire, wind, dust, and water resisting or retardant requirements.

20 The description of the objects of the invention herein is such as to be readily understood as they are interwoven or interspersed with the detailed description of the parts of the device that are clearly shown 25 in the accompanying several sheets of drawings, in which,

Figure 1 is a horizontal-section taken on the dotted-line a, a , of Fig. 2, but showing the customary two sashes, however, broken 30 off and with their lower frame-bars in plan, and, also, with the upper-sash as though at the bottom of the frame, although its adjacent balancing-weight is down in the 35 position it occupies when said upper-sash is in its normally-closed position, as in Fig. 2; Fig. 2, an outside elevation of the entire window, showing no particular details; Fig. 3, a detached horizontal-section of my compensating, auxiliary, adjustable, side run- 40 way strip that is shown in Fig. 1 and taken on a line either above or below that of Fig. 2; Fig. 4, a detail elevation of one of the adjusting-screws for the auxiliary run-way strip seen in Fig. 1, but with its lock-nut 45 separated therefrom; Fig. 5, an inside-elevation of the window, omitting the lower-sash and showing one of the upright-sides of the frame broken away at its lower portion to display the weight at that side for 50 the closed-position of the upper-sash, the removable cap-plate in the weight man-hole, and showing the upper end of said upright-side broken away to disclose the ready man-

ner of mounting a sheave or pulley for the weight-rope; Fig. 6, a vertical, sectional-elevation taken on the perpendicular dotted-line b, b , of Fig. 5, but including both sashes therein and both in raised-positions, and with the cap-plate removed from its weight hand-hole at the bottom of the runway used by the upper-sash and the latter being shown as partly lowered; Fig. 7, a horizontal section, similar to Fig. 1, but on a smaller scale, and taken on the dotted-line c, c , of Fig. 6, omitting the sashes; Fig. 8, a horizontal, detail section of the removed weight cap-plate of Fig. 6, and Fig. 9, a vertical, detail sectional-elevation of the said cap-plate seen in Fig. 8.

It will be observed that the sheet-metal 70 is shown in these views in single-line, diagram form instead of using, cross-section lines, and it will, of course, be understood that where spaces occur between some of the surfaces the latter should be in actual 75 contact and especially in parts that interlock or fold and snugly fit one within the other, although where parts slide they should be practically contiguous but free to reciprocate without undue frictional-contact.

1 indicates the sill; 2 and 3 the upright side-members; and 4 the top-member or head of the frame of the window, all made of sheet-metal bent into the desired shapes 85 and in hollow, or in insulator air-chamber form wherever possible and feasible.

Each of the two hollow uprights 2 and 3 is composed of a metal sheet whose opposite vertical longitudinal edges 5 and 5^a, are 90 separated at the rear of the uprights and then formed into inwardly-turned, almost lapping or closed hooks that angle at 6. The metal from hooked-edge 5 then takes a straight course 7 forward; then angles at 8; 95 then a short straight lateral outward course 9; then angles at 10; then takes another straight course 11 forwardly to an angle 12; then takes a straight course 13 inwardly, at the outer end of which a U-shape bend is 100 made at 14 to form a narrow vertical slit or groove 15; then takes another straight course 16 inwardly to an angle 17; then takes a straight course 18 rearwardly to an angle 19 where an acute-angled course 20 forwardly 105 is taken to an angle 21 when another straight

rearward course 22 is taken to an angle 23 that leads to a short, central transverse course or ligament 24 that thence angles at 25 and advances forwardly in a straight line 26 (corresponding to the part 22 that it parallels and alines) until an angle 27 is reached (corresponding to the angle 21 and having an acute-angled bend 28 that alines with the part 20) and thence angles at 29 (corresponding to angle 19) whence it takes a forward straight course 30 (corresponding to the opposite straight course 18) and thence angles at 31 (corresponding to angle 17) whence is taken a lateral, outward straight course 32 (corresponding to part 16) and thence angles at 33 into a short forward straight course 34, that then angles at 35 with another short lateral, outward straight course 36 till reaching an angle 37, whence another straight rearward course 38 is taken to an angle 39 (corresponding to the angle 10) and another short inwardly-lateral straight course 40 (corresponding to part 9) to an angle 41 (corresponding to and alining with angle 8) whence it takes a long straight rear course 42 (corresponding to the straight course 7 that it parallels and alines) until an angle 43 is reached (corresponding to angle 6) and finally ending in the said hooked-edge 52.

A bridge-plate or closure-back 44 has its opposite vertical edges hooked at 45, 45 to engage the hooked-edges 5 and 5^a of the hollow-walled upright, and an inwardly-disposed vertical crimp 46 is centrally made in this closure-back to form a stiffening and strengthening rib, as well as a sash-weight separator to prevent the weights twisting, turning and colliding in their respective rear guide-ways.

The vertical limbs or parts 16 and 32 form the joint or back-walls of the channel run-ways for the side edges or slides of the sashes, and the parts 18, 20, 22, 24, 26, 28 and 30 form inwardly-facing vertical chambers or pockets at the vertical centers of each of the two hollow uprights 2 and 3 to accommodate vertical, auxiliary, compensating, run-way slide-strips and guard-fillers that I shall now describe. These run-ways and guard-fillers are each composed of a central-member 47 that has along its opposite edges a pair of rearwardly-extending members 48, 48 that have short lateral-members 49, 49, extending therefrom, which, in turn, have rearwardly-extending U-shape members or guard-fillers proper 50, 50, whose pairs of limbs are brought somewhat closely adjacent so as to provide narrow slits or pockets for the accommodation of inwardly-turned reinforcing or stiffening ends 51, 51, as best seen in Fig. 3. The parts 51 extend beyond the line of the short lateral-members 49 to form the constant guards or closure-barriers proper of the run-ways and will be

still more explicitly referred to hereinafter in connection with the adjusting devices and the sashes. A vertical U-shape member 52 extends backwardly from the central-member or parting-strip 47 into the narrow, rear portion of each of the said vertical chambers or pockets composed of the parts 22, 24 and 26, the extended limbs of the U-shape members 52 being adapted to slide within the walls 22 and 26 of said reduced rear portion of the pockets and have suitable frictional-bearings therein to prevent undue looseness or rattling. A capping, stiffening or reinforcing member is applied to the rear portion of each of the two vertical pocket-structures, and is composed of a straight central-member 53 that has forwardly-projecting side-members 54 and 55, that engage the members 22 and 26 and thence extend laterally into corresponding right-angled members 56 that take over the acute-angled shoulders 20 and 28 of the main-frames of the uprights. The acute-angled shoulders 20 and 28 provide a deeper scope of movement for the rearwardly-extended portions 50, 50 and 52 of the auxiliary run-way slide-strips and guard-fillers, and are important features in the adjustment of the said run-way guard-fillers that provide for the least lateral undue play of the sashes.

In adjusting and connecting the run-way guard-fillers a series of horizontal screws 57 are used, the respective inner ends of whose shanks are threaded and engage threaded openings in vertical reinforcing metal bars 58 that give the desired foot-hold or bearing for the screws. Said threaded ends of the screws pass through the rear walls or parts 24 and 53 of the run-way guard-fillers, and the fore-ends of the said screws are cross-cut and threaded for the engagement of the lock-nuts or caps 59 that have cross-cuts 60 that are intended to aline with the cross-cuts in the screws themselves for convenience in turning the screws to and from setting-position. A stop-collar 61 is provided near the fore-end of each of the screws 57 to bear against the inner face of the cross part or head of the U-shape rear slide-member 52 of the run-way guard-filler device, so that when a screw-driver is inserted in the cross-cut 62 and the alined cross-cut at the fore-end of the screw, to turn it either way, (the lock-nut 59 being slightly loose); the rear threaded-end of said screw turns in the rigid vertical bar 58 to carry the run-way guard-filler toward and away from said reinforced rear-pocket of the main-frame of the hollow upright. Thus any slight or other variations in the fitting of the sashes in the channel run-ways can be readily adjusted to a nicety, looking always, however, to the free and easy sliding-movements of said sashes in opening and closing the window, and with a view

to provide a proper closure or barrier against the entrance of fire, smoke, dust, wind and water into the building-structure.

The window-sashes are both made alike 5 along their opposite vertical edges or side-stiles as well shown in Fig. 1, in which A indicates the lower-sash and B the upper one. Their frames are of hollowed, sheet-metal structure and they are provided with 10 slightly tapered or spreading grooves, as shown at C, for the glass-lights D, whereby the use of putty or cement can be made against entrance of fire and other objectionable elements from without along those 15 lines. The vertical edges of the sashes are formed of metal sheets whose opposite vertical edges at both corners are bent into double-hooks E, and fillers or bridge-pieces F are provided that have opposite out- 20 wardly-disposed hook-edges G adapted to interlock with the said double-hook corners E of the vertical edges of the sashes. These hook-members are, of course, closed or brought tightly together to assure proper 25 joints free from leakage of any kind, and they are strong and stiff for use in guiding the sashes in the adjustable channel run-ways provided in the side-joints of the up- 30 rights of the window-frame previously de- scribed.

A metallic, hollow, coiled bead or side-strip H is provided on the part 13 of each of the hollow-uprights, and it has an extension I that engages the slit 15, such extension also projecting laterally at J to form 35 a broad bearing-surface or weather-strip for each of the opposite, extended side-edges or flanges of the inner face of the side-slides of the lower-sash, as best shown in 40 Fig. 1. A series of screws K is used in the side-strips or beads H for fastening them in place on the parts 13, and reinforcing bars or backings L are also used on the inner faces of said parts 13 to receive the inner 45 threaded-ends of said screws and give them the desired bearing.

A deep, bearing, channeled run-way surface is provided for the vertical side-exten- 50 sions on the inner corners of the side-stiles 55 of the sashes, especially along the vertical center or parting-strip of the uprights 2 and 3 of the frame, the parts or members 48, 49 and 51 forming constant guide-ways that prove effective for the desired free sliding-engagement of the adjacent side-exten- 60 sions or flanges of the two sashes that are not affected by expansion or contraction nor by the settling of the building-structure after the window has been installed for use. 65 The adjustment of the run-way guard-fillers to and from the side-stiles of the sashes corresponds to the variations that occur in the relations of said side-stiles to the said run-way fillers, consequent on said contraction, 85 expansion and settling, the rear extensions

or guards-proper formed by the parts 50 of the auxiliary-filler being the essential ones of my invention herein to fill and compensate for any space or gaps incurred by the said expansion, contraction or settling common to wooden and metal window-structures alike and rendering them greatly defective for use.

The channel run-ways are continuous and of one piece of material from top to bottom, so that there is no obstruction whatever to the free and smooth sliding or perfect running of the sashes at all times. The balancing-weights M and N are readily placed in their proper rear-chambers through the openings O provided at the lower ends of the jambs at either side of the run-ways, and shown in Figs. 5, 6 and 7, and without removing either sash, and the rear-exten- 80 sions of the pockets for the channeled run-ways lie between the weights to form continuous partings that prevent the twisting and clogging of the weights. Capping- 85 plates P are used in the weight man-holes O, as shown in detail in Figs. 8 and 9, and, also, in place in Figs. 5, 6 and 7, such plates having side-flanges p that extend through said openings O, and opposite end-exten- 90 sions p' p', the latter having holes p² for the insertion of counter-sunk screws p³ 95 whose inner threaded-ends engage the reinforcing bearing-plates p⁴ on the inner faces of the joints.

A pendent fender-formation Q extends from the lower inner edge of the lower-sash 100 A for overlapping-engagement with an overlapping or undercut sill formation or projection R, as best seen in Fig. 6, but does not contact with the sill, to avoid entrance of fire, draft and other objectionable ele- 105 ments along said lower edge or bottom of the lower-sash.

Interlocking hook-formations S and T are provided on the meeting-rails of the two 110 sashes to guard against the entrance of fire and other objectionable elements at that point in the window-structure.

The usual sash-cord pulleys U are mounted in the tops of the uprights 2 and 3, as seen in Fig. 5, wherein the pulleys may 115 be easily replaced should it become necessary to do so, and it is further necessary to take either sash out of the frame to insert or remove the weights.

In the use of my invention herein there is absolutely no reason for or danger of the sashes sticking or getting too tight in the run-ways, and the adjustable run-way slides with their rear guard-extentions can never fail to prevent the entrance of fire, and other like objectionable elements from without. Any one can easily perform the adjustment of the run-way slides, and it will not be necessary at any time to plane or otherwise 125 remove any of the side-surfaces of the side- 130

stiles whatever on account of varying widths of sashes used.

I claim:—

- In a sheet-metal window-structure, slide-
5 able sashes each having laterally-extending
tongues provided along its opposite
side-stiles, hollow upright side-frames each
having a central, vertical chamber or channel
that has an inwardly bent or reduced
10 rearward extension, independent, vertical,
doubly-grooved track-members freely ar-
ranged in said side-frame chambers or
channels and adapted to extend therefrom
for the sliding-engagement of said tongues
15 on the sash-stiles, telescopic, angular filler-
members having reduced rear-extensions
coinciding and engaging with the rear-ex-
tensions of the side-frame chambers, U-
shape guard-fillers extending rearwardly
from the track-members within said cham-
bers and their rear-extensions, and means
comprising a series of horizontal collared-
screws and pierced vertical bars adapted for
engagement by said screws to adjustably-
support the said track-members and their 20
filler-members in said chambers whereby the
said guard-fillers and track-members may be
moved laterally to and from the tongued
edges of the sash-stiles to compensate for
wear and to allow for varied widths of sashes 25
in properly fitting and operating them in
the window-frame.

EDWIN R. PROBERT.
